UNITED STATES PATENT OFFICE.

WALTER G. HAAS, OF DAYTON, OHIO.

PAPER BOX.

SPECIFICATION forming part of Letters Patent No. 700,418, dated May 20, 1902.

Application filed December 10, 1901. Serial No. 85,364. (No model.)

To all whom it may concern:

Be it known that I, WALTER G. HAAS, a citizen of the United States, residing at Dayton, in the county of Montgomery and State of Ohio, have invented certain new and useful Improvements in Paper Boxes, of which the following is a specification.

The object of my invention is to construct a box of cardboard or other similar material, which is provided with an improved form of corner-lock, so as to hold the parts securely in position, which is constructed in such a manner as to improve and strengthen the box.

The features of my invention are more fully set forth in the description of the accompanying drawings, forming a part of this specification, in which—

Figure 1 is a plan view of a blank for a combined box and cover. Fig. 2 is an inside perspective view showing one of the corner-locks folded in. Fig. 3 is a side elevation showing one end in the act of locking and the opposite turned up in position for bending the lock-flap. Fig. 4 is a modification of Fig. 1 of the box proper without cover.

In the blank shown in Fig. 1, A represents the bottom of the box; B, the cover.

b b' represent the sides; a a', the ends; c c', the folding extension of the ends.

d d' d² d³ represent the folding and locking flaps.

e represents a slit cut diagonally to the center of the corner-piece, and e' a scored line for bending over the same, so that the slit edge will lie in the plane shown by dotted lines e², Fig. 3.

h h' h² h³ represents slits into which the corner-locks engage. Each of the four corner-locks are duplicates. As shown in Fig. 1, the locking-slits h³ are in the end sections a a' and the slits h² in the side section b'. The cover B and the fold-over flaps c c' of the end pieces protect the locking-slits and prevent their tearing out.

The box is put together in the following manner: The V-shaped piece v, lying between the slit e and the scored line e', is bent over so that the marginal edge of the V lies along the diagonal line e², as shown in the right-hand flap, Fig. 3. The corner-flap is then turned

and the V-shaped tongue or lock is entered into the diagonal slot h', as shown at the left-

hand end of Fig. 3. When this tongue has been passed clear through the slot, then the turned-over V-section v is folded back. In boxes constructed of heavy material it recedes into position of its own accord, and the marginal edge of the corner-flaps rests on the bottom of the box, making a secure bracing-lock and supporting the locks against vertical strains.

When it is desired to make a box without covers or folding-over sections, it is constructed as shown in the modification Fig. 4, in which h h' represent the locking-slits; l l', the folding corners; m m', the folding-over sections of the locking-flaps. The parts are put together in the same manner as the other form of box, and the folding-over pieces are turned back, with their lower edges resting on the bottom of the box. The locking-slits in this case are located as shown in said Fig. 4. This form of box is more easily unlocked and folded down than the form shown in Figs. 1, 2, and 3.

Having described my invention, I claim—

1. In a paper box, a corner-lock consisting of slots formed in the sides thereof, a substantially rectangular-shaped locking-flap at each corner intermediate of the sides, each flap being diagonally slotted and scored so as to be folded upon itself, threaded through its respective slot in the side and unfolded in the inside of the box, against the bottom and into the corner of the box forming a combined corner lock and brace, substantially as specified.

2. In a paper box a corner-lock consisting of slots formed in the sides thereof, a substantially rectangular-shaped locking-flap at each corner intermediate the sides, each flap having a diagonal slot at its inner corner, and a scored line formed on said flap whereby the flap can be doubled upon itself, threaded through its respective slot in the side and unfolded in the inside of the box against the bottom and in the corner of the box, forming a combined corner lock and brace, substantially as specified.

3. In a paper box, a corner-lock consisting of slots formed in the sides thereof, a substantially rectangular-shaped locking-flap at each corner intermediate the sides, each flap being provided with a slot extending through

its inner corner toward the middle of the flap and a scored line extending from the end of the slot angularly toward an adjacent corner of the flap, whereby the severed end of the flap can be folded outwardly upon itself and threaded through its respective slot in the side and unfolded in the inside of the box against the bottom and into the corner of the box, forming a combined corner lock and brace, substantially as specified.

4. In a paper box a corner-lock consisting of slots formed in the sides thereof, a substantially rectangular-shaped locking-flap intermediate the slotted sides, each flap having a slit and a scored line converging inwardly

from the base of the locking-flap and terminating at a point of intersection in the middle portion of the flap, whereby the slotted portion of the flap may be folded upon the body of the flap along said scored line, the doubled flap threaded through its adjacent side slot and unfolded upon the interior of the box forming a corner-lock, substantially as specified.

In testimony whereof I have hereunto set my hand.

WALTER G. HAAS.
